US0D1109334S

(12) **United States Design Patent** (10) **Patent No.:** **US D1,109,334 S**
(45) **Date of Patent:** ** *Jan. 13, 2026

(54) **MONITOR ATTACHMENT**

(71) Applicant: **KONINKLIJKE PHILIPS N.V.**,
Eindhoven (NL)

(72) Inventors: **Lei Yang**, Eindhoven (NL); **Liang Yong Tang**, Nanshan (CN); **Fabian Benedikter**, Oberwil-Lieli (CH)

(73) Assignee: **KONINKLIJKE PHILIPS N.V.**,
Eindhoven (NL)

(*) Notice: This patent is subject to a terminal disclaimer.

(**) Term: **15 Years**

(21) Appl. No.: **29/840,809**

(22) Filed: **Jun. 1, 2022**

(51) LOC (15) Cl. **24-02**

(57) **CLAIM**

The ornamental design for a monitor attachment as shown.

DESCRIPTION

FIG. 1 is a perspective view of a monitor attachment;

FIG. 2 is a front view of a monitor attachment;

FIG. 3 is a rear view of a monitor attachment;

FIG. 4 is a bottom view of a monitor attachment;

FIG. 5 is a top view of a monitor attachment;

FIG. 6 is a left side view of a monitor attachment;

FIG. 7 is a right side view of a monitor attachment; and,

FIG. 8 is a rear perspective view of a monitor attachment.

1 Claim, 6 Drawing Sheets
